UNITED STATES PATENT OFFICE

VIRGINIA HAMILL, OF NEW YORK, N. Y., ASSIGNOR TO W. S. LIBBEY COMPANY, A CORPORATION OF MAINE

DESIGN FOR A TEXTILE FABRIC

Application filed November 4, 1929. Serial No. 33,330. Term of patent 3½ years.

To all whom it may concern:

Be it known that I, VIRGINIA HAMILL, a citizen of the United States and a resident of the city, county, and State of New York, have invented and produced a certain new, original, and ornamental Design for a Textile Fabric, of which the following is a specification, reference being had to the accompanying drawing, forming part thereof, wherein:

I claim:

The ornamental design for a textile fabric, as shown and described.

VIRGINIA HAMILL.
